UNITED STATES PATENT OFFICE.

JOHN JACK GARIBALDI, OF NEW YORK, N. Y.

BOTTLE-CAPPING MACHINE.

Application filed March 3, 1925. Serial No. 12,951.

My invention relates to a bottle capping machine and although capable of use generally as a capping machine, it is more particularly designed for capping a form of 5 non-refillable bottle.

The general object of my invention is to provide a bottle capping machine having novel means for properly placing the cap on the bottle; together with coordinated 10 means to subject the cap to pressure in a manner to cause the cap to conform to the beaded neck of the bottle.

The nature of my invention and its distinguishing features and advantages will 15 appear as the description proceeds.

Reference is to be had to the accompanying drawing forming a part of this specification, it being understood that the drawings are merely illustrative of one example 20 of the invention.

Figure 1 is a side elevation of a bottle capping machine embodying my invention;

Figure 2 is a front elevation of said machine;

Figure 3 is a horizontal section on the line 3—3, Figure 2;

Figure 4 is a detail in vertical section as indicated by the line 4—4, Figure 3.

In carrying out my invention in accordance with the illustrated example, a back plate 10 is provided adapted to be secured by any suitable means to a wall or like support conventionally indicated in Figure 1. In front of the back plate 10, which 30 usually is disposed vertically, is a table 11 on which the bottle A may rest, said table having a flange 12 and having within said flange a felt, leather, or other suitable covering 13 to overcome any tendency 35 of the table to revolve independently of the bottle and to require the bottle to turn with the table. The table 11 is on a spindle 14 turning in a bearing 15 on a bracket 16. Said bracket 16 is made vertically adjustable being provided with bolts 116 passing 40 through slots 216 in said bracket and into the base 10 whereby the bracket 16, the spindle 14, and table 11 may be adjusted vertically to suit bottles of different heights 45 and give the table and bottle proper relation to the capping means hereinafter described.

Suitable means is provided for turning the spindle 14 and its table 11. In the illustrated example a bevel pinion 18 is affixed to the reduced end 17 of spindle 14

and meshes with a bevel gear 19 on a transverse shaft 20 adapted to be driven manually or by power, there being shown a pulley 21 to receive a belt (not shown). 60

Above the table 11 and in line therewith is a capping head 22 between which and the table 11 the bottle A is accommodated. Said capping head 22 is on a vertically reciprocating spindle 23 operated by a bell-crank lever 24 connected with said spindle by a link 25. Said lever 24 is fulcrumed as at 26 on a forked arm 27 of a bracket 28 secured by bolts 29 or equivalent means to base plate 10. 70

With the above described arrangement a bottle A is seated on the table 11 at which time the capping head 22 is held in a raised position by the lever 24. The cap B having been placed on the bottle the lever 24 75 is operated to force the capping head 22 downwardly over the bottle cap B until said cap is pressed firmly home onto the bottle neck. 80

I provide means coordinated with the capping head 22 and table 11 for causing the bottle cap B to conform to the bead of the bottle neck as indicated at b in Figure 2 for which purpose the following mechanism is provided: 85

On a lateral extension 30 of base 10 is secured a casting 31 which has a guideway 32 in which operates a slide 33, the rear end of which has a slot and pin connection with a lever 34, there being a slot 35 in said lever and a pin 36 on said slide 33 positioned in said slot. The lever 34 is fulcrumed at its inner end as at 37 to an arm 38 on casting 31. The arrangement is such that the operation of the lever causes the slide 33 to be reciprocated in the guideway 32 toward or from the coincident axes of the capping head 22 and table 11. The forward end of the slide 33 is formed with a fork 39 in which is disposed a peripherally 90 grooved beading roller 40 on a shaft or transverse pin 41 passing through said fork and through said roller. To center the roller 40 a washer 42 is employed at each side between the same and the arms of the fork 100 39, said washer having alternate fingers 43, 44 bent in opposite directions to frictionally engage respectively the inner surfaces of the members of fork 39 and the side surfaces of the wheel 40. When the cap B 110 has been emplaced on the bottle A as described, the lever 34 is caused to move the

roller 41 to bear against the bottle cap B at the bead *b* of the bottle neck. While the roller 40 engages the cap B the spindle 17 is revolved by the gears 18, 19 for turning the table 11 and bottle A as well as the bottle cap B.

The capping head 22 is so arranged that it turns with the table 11, bottle A and cap B, said head 22 being swivelled to the 10 spindle 23. Said spindle 23 has an annular groove 123 within the tubular shank 122 of the capping head 22 and a pin 45 passes through the shank 122 tangentially to the annular groove 123 to lie partly in 15 said groove and partly in the shank 122. The lower end of the head 22 when the bottle A is clamped in position is in a plane above the bead *b* leaving clearance for the operation of the beading roller 40. 20 I would state in conclusion that while the illustrated example constitutes a practical

embodiment of my invention, I do not limit myself strictly to the exact details herein illustrated, since, manifestly, the same can be considerably varied without departure 25 from the spirit of the invention as defined in the appended claim.

Having thus described my invention, I claim:

A reciprocable beading roller unit for 30 bottle capping machines, including a transverse slide having a fork in one end thereof, a beading roller turnably mounted in said fork, a pin on which said beading roller turns, centering means for the beading roller including washers on said pin between the roller and the fork, said washers having fingers bent alternately in opposite 35 directions into frictional engagement with the fork members and with the roller.

JOHN JACK GARIBALDI.
